UNITED STATES PATENT OFFICE.

RUDOLPH MUELLER, OF KANSAS CITY, MISSOURI, ASSIGNOR TO GOODENOW-BROOKFIELD KNITTING COMPANY, OF KANSAS CITY, MISSOURI, A CORPORATION OF MISSOURI.

TRIM FOR KNIT GARMENTS.

1,054,233.

Specification of Letters Patent. Patented Feb. 25, 1913.

Application filed February 6, 1912. Serial No. 675,852.

To all whom it may concern:

Be it known that I, RUDOLPH MUELLER, a subject of the Emperor of Germany, residing at Kansas City, in the county of Jackson and State of Missouri, have invented certain new and useful Improvements in Trim for Knit Garments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to knit trim for garments and more particularly to a trim for finishing the edges of garments cut from stock knit material in which the edges to be finished are not selvaged.

When the garment has a selvage edge it is a comparatively simple matter to sew trim thereto, but when the edge is ragged the trim must be set back from the raw edge and particular care given to the sewing or the threads will pull through the edge of the garment when the latter is used. The usual practice for protecting the ragged or cut edge is to use a piece double the intended width of the edge or trim, fold it, and sew it up over the front outside edge of the garment and over the back under side edge. This form of trim must then be pressed and button holes made through two thicknesses of cloth, which usually have a piece like cambric inserted between them to hold the button holes. This double trim signifies, as a rule, cheapness, and only on high grade full fashioned garments can single thickness trim be put on.

This invention, however, allows the application of a single thickness trim on a cut, not full fashioned, garment. In other words, it allows a cheap cut garment to be equipped with a single thickness trim in imitation of full fashioned garments. For example, in full fashioned sweater coats the edges of the coat sections are selvaged and single thickness trim applied thereto, to give the garment the full fashioned appearance.

By means of my invention a sweater coat

formed of cut sections can have my improved form of trim applied thereto, and when so finished will have the appearance 55 of single thickness trim, thereby giving the garment the full fashioned appearance.

More specifically my improvement may be termed a "split trim", in that it comprises a body portion divided at one edge 60 to form two separate plies which are knit integral with the body and adapted for receiving the raw edge of the garment therebetween. It is apparent that with such a structure, both edges of the trim may be 65 selvaged so that they may be sewed securely to the garment, and that button holes may be sewed in the one piece body.

While the present invention relates solely to the "split trim", I have illustrated in 70 some detail the kind of stitch and the knitting machine used in its manufacture, in order that the trim may be more easily and clearly understood.

In the accompanying drawings:—Figure 75 I shows a lower front corner of a garment finished with my improved trim, part of the trim being folded back to more clearly show the manner of its application to the garment. The view merely shows design of 80 the garment and trim and is not intended to illustrate any particular stitch. Fig. II is a sectional view on the line II—II, Fig. I. Fig. III is a perspective view of a piece of the trim. Fig. IV is a face view of one 85 side of the trim, shown coarsely knit to better illustrate the stitch. Fig. V is a similar view of the opposite side of the trim. Fig. VI is a cross section of the trim, the stitching not being shown in order to illustrate the split more clearly. Fig. VII is an enlarged detail view of one tread of one of the bifurcated or ply members. Fig. VIII is a similar view of one thread of the body portion. Fig. IX is an enlarged and coarsened view of a part of the body member, showing the connection of the several 95 threads. Fig. X is a diagram of the travel of the yarn guides for forming the back split or ply member. Fig. XI is a similar 100 diagram for the front split or ply. Fig. XII is a similar diagram for the body portion. Fig. XIII is a perspective view of portion of the needle bars and yarn guides,

showing the course of one of the threads in the body portion and a thread in each of the ply portions of the trim.

Referring first to the trim and the garment to which it is applied, 1 designates a portion of a knit garment, the material for which is cut from stock knit goods so that the edge 2 is left raw or ragged.

3 designates the trim, which comprises a body portion 4 having separate integral ply or lip members 5—5' running along one of its longitudinal edges, the outer edges of the plies being free to form a pocket 6 for receiving the raw edge of the garment body.

15 In forming the trim, as will presently be described in detail, the body and ply members are knit simultaneously by the same double sets of needles, but by separate threads, each of which is controlled by a separate yarn guide, the ply stitches being alike but differing from the body stitch although united with and continuing therefrom at the base of the split. The machine I have found best adapted for this work is 20 that known as the Raschel warp knitting machine, wherein the trim may be knit longitudinally so that its beginning or outside body edge and the ply or inside edges are selavage edges. This machine, adapted for 25 knitting my split trim, comprises a pair of needle bars 7, arranged in spaced relation and so combined with an operating mechanism (not shown) that when one of the bars is raised the other is lowered, and vice versa.

30 The needle bars are adapted to slide vertically on stationary plates 8, which are spaced to provide a channel 9 therebetween, and have lips 10 projecting laterally from their upper edges to provide needle sockets 11.

35 40 Mounted in each of the needle bar leads are needles 12, of ordinary construction, the upper ends of which are adapted for travel in the individual sockets 11 and for projection above the top of the plates 8 when at the top of their travel.

45 13 designates yarn guides which are arranged above the needle bars and have lateral guide plates 14 provided with apertures 15, and depending arms 16 provided with eyelets 17, there being a guide arm 16 for each plate aperture 15. The yarn guides are three in number and are adapted for horizontal reciprocation in timed relation to the vertical reciprocation of the needle bars in order to carry the yarn to proper needles.

50 55 In the knitting operation, yarn is run to each needle bar independently of the others, so that the motion of each of the bars may be independent, although operated in harmony with the others, so that we may consider that the actual knitting mechanism comprises three sets of parts, one for the front ply or split portion of the trim comprising one of the yarn guides with its oscillating mechanism and one needle set, one

for the back ply comprising a different yarn guide with its oscillating mechanism, and one needle set, and one for the body portion comprising the third yarn guide with its oscillating mechanism and both needle sets, 70 from which it is seen that the same needles are used for all three parts of the trim and that the differences in stitch or structure are secured through the action of the individual yarn guides. More specifically, in forming 75 the front split portion of the trim the guide carrying the yarn for this portion is moved in such relation to the movement of the needle bar that starting with a yarn passed between two needles, the yarn is looped around the adjacent needle on the right, passed by the adjacent needle on the left and looped around the next needle on the left, this operation being repeated to produce the desired stitch.

80 From the foregoing description, and from the diagram of the stitch for the front ply shown in Fig. XI, it is apparent that it requires two eyelets to complete the stitch in the front split portion and that a stitch 90 just described is held or formed on every second needle, the next adjacent stitch occupying the intermediate needle and the next needle beyond. The back split portion, a diagram of which is shown in Fig. X, is 95 formed in the same way as the front, except that it is offset one needle from that of the first split portion, the yarn guide carrying the strands for the back split portion moving from right to left while the yarn guide 100 carrying the strands for the front split portion move from left to right and vice versa, but one needle in advance. In forming the body portion of the "trim", the yarn "walks" on both sets of needles, first in 105 the front, then in the back, then the front and then the back, this action being continuous. Also in this portion I prefer to have twelve strands, each strand comprising two yarns each, so that the finished "trim" will 110 be of uniform thickness. At the point where the two split portions connect to the body portion, loops of yarn in the front and back splits will intermesh with loops in the body; the strands on the body portion on 115 these particular needles comprising only one yarn so as to keep the surface uniform and prevent a ridge running through the "trim" at this point.

120 In comparing the stitch in Fig. VII with the diagrams shown in Figs. X and XI, it will be seen how the yarn first loops from left to right, then loops from right to left in a continuous chain.

125 The body stitch shown in Fig. VIII may be compared with the diagram shown in Fig. XII, in the same manner, to illustrate that the yarn first makes a loop from left to right in the front, moves to left, makes another loop from left to right, moves to 130

left and makes a loop from right to left, moves to right and makes a loop from right to left, then moves to right and makes the same loop from left to right that it started with.

The fabric formed as above will not ravel as each stitch locks the other, consisting, in this particular case, of twenty-eight separate strands of yarn which extend from end 10 to end of the fabric regardless of how long it is made. A fabric similar to this, which would be produced on an ordinary machine, would consist of one continuous yarn running back and forth from one end of the 15 trim to the other, the length of the trim being limited by the length of the machine.

Having thus described my invention and the manner of producing the same, what I claim as new therein and desire to secure by 20 Letters Patent is:

1. A split trim fabric, comprising a body portion having a bifurcated side comprising selvage edges.
2. A split trim fabric comprising a knit body having an integral bifurcated side portion comprising selvage edges.
3. A split trim fabric comprising a body portion having a bifurcated side comprising selvage edges, and wherein the combined 30 thickness of the split members is equal to that of the body portion.
4. In split trim fabric, a body portion formed of double strands; and a bifurcated portion integral with the body members, the bifurcated portion being formed of single strands and provided with selvage edges.
5. In split trim fabric, a body portion of double thickness, a bifurcated portion having members of single thickness, and single 40 strands connecting the body and bifurcated portions and following the stitch of the

body portion, both the body and bifurcated portions having selvaged longitudinal edges.

6. A trim strip for garments comprising a body portion having a selvage edge and a 45 plurality of plies, each having one edge interlocked with the same longitudinal edge of the body portion.

7. A trim strip for garments comprising a body portion and a plurality of plies 50 intimately knit with the body portion and extending along the same longitudinal edge thereof the full free edges of the plies being selvaged, for the purpose set forth.

8. A trim strip comprising separate plies 55 having free outer edges, forming a pocket therebetween, and having inner edges merging into a single body portion, the plies and body portion having selvaged edges for the purpose set forth.

9. A trim strip comprising a body portion, and separate plies extending along and interlocked with the same longitudinal edge of the body portion, the stitches of the plies 65 being alike but differing from that of the body portion, and both having selvaged free edges.

10. A trim strip comprising a body portion having plies knit intimately therewith, the plies being free of each other and merging with the body at one edge, the stitch of the plies differing from that of the body and being adapted to form a thinner fabric, the 70 body and plies having selvaged longitudinal edges.

In testimony whereof I affix my signature in presence of two witnesses.

RUDOLPH MUELLER.
